US00D858775S

(12) **United States Design Patent** (10) Patent No.: **US D858,775 S**
(45) Date of Patent: ** Sep. 3, 2019

(54) **BLOOD TESTING APPARATUS**

- (71) Applicant: **Roche Diagnostics Operations, Inc.**,
Indianapolis, IN (US)
- (72) Inventors: **Craig Ian Wightman**, Bristol (GB);
Johann Florian Wassermann, Horgen
(CH); **Michael John Unwin**,
Bishopston Bristol (GB)
- (73) Assignee: **Roche Diagnostics Operations, Inc.**,
Indianapolis, IN (US)
- (**) Term: **15 Years**
- (21) Appl. No.: **29/647,953**
- (22) Filed: **May 17, 2018**

Related U.S. Application Data

- (60) Continuation of application No. 29/607,658, filed on Jun. 15, 2017, now Pat. No. Des. 820,989, which is a continuation of application No. 29/583,390, filed on Nov. 4, 2016, now Pat. No. Des. 804,033, which is a division of application No. 29/512,655, filed on Dec. 22, 2014, now Pat. No. Des. 787,067.

(57) **CLAIM**

The ornamental design for a blood testing apparatus, as shown and described.

DESCRIPTION

FIG. 1 is a right side, front perspective view of a blood testing apparatus illustrating our new design;

FIG. 2 is a left side, rear perspective view of FIG. 1 thereof;

FIG. 3 is a front view of FIG. 1 thereof;

FIG. 4 is a rear view of FIG. 1 thereof;

FIG. 5 is a bottom plan view of FIG. 1 thereof;

FIG. 6 is a top plan view of FIG. 1 thereof; and,

FIG. 7 is a left side view of FIG. 1 thereof, the right side being the same.

The broken lines in the drawing views illustrate portions of the blood testing apparatus that form no part of the claimed design.

1 Claim, 7 Drawing Sheets
